UNITED STATES PATENT OFFICE

REUBEN L. WAXLER, OF HOUSTON, TEXAS

BLOW-OUT PREVENTER

Application filed September 6, 1930. Serial No. 480,170.

This invention relates to a novel blowout preventer.

One object of the invention is to provide novel means for forming a fluid tight seal between an outer pipe or casing, in a well bore, and the drill stem, or other inner pipe, in said bore so as to prevent the escape of fluid, under the influence of internal pressure, out between said casing and inner pipe.

10 A further feature of the invention resides in the provision of means for controlling a well having internal gas pressure which may be quickly and securely adjusted into active position between the outer and inner pipe in the well and securely fitted about the inner pipe to form the desired seal and which may be operated at a distance from the well so as to avoid unnecessary risks of injury to workmen.

20 A still further feature of the invention resides in the provision of a blowout preventer of the character described that is of very simple construction and may be cheaply produced and which is positive in operation, of sturdy construction and whose parts may be readily removed and replaced.

With the above and other objects in view the invention has particular relation to certain novel features of construction, operation, and arrangement of parts, an example of which is given in this specification and illustrated in the accompanying drawings herein.

Figure 1 shows a vertical sectional view 35 of the apparatus, shown in open or inactive position.

Figure 2 shows a cross sectional view taken on the line 2-2 of Figure 1.

Figure 3 shows a vertical sectional view 40 taken on the line 3-3 of Figure 4 and Figure 4 shows a vertical sectional view showing the apparatus in active or closed position.

45 Referring now more particularly to the drawings, wherein like numerals of reference designate the similar parts in each of the figures, the numeral 1 designates a housing, which is preferably of a general rectangular form in cross sectional contour, and which is mounted on and may be

formed integrally with the upper section 2 of the well casing which extends down into the well. This housing is closed at one end by the removable end plate 3 and at the other end by the removable cap 4, said plate and cap being suitably bolted to the housing. Within the housing, and at the bottom thereof, there is the downwardly converging seat 5 surrounding which there is the upwardly and outwardly flared guide 6.

There is an actuating shaft 7 which works through and has a swivel connection with the outer end of the cap 4 and whose outer end 8 is formed to receive a wrench. The inner end of this shaft is coarsely threaded and works through a correspondingly tapped hole in the yoke 9. This yoke is disposed transversely across the casing and has the end plates 10, 10 which work adjacent the opposite sides of the housing. The said sides of the housing have the bearing plates 11, 11 welded or otherwise secured thereto, and these bearing plates have the central vertical bearing grooves 12, 12 whose lower ends are turned outwardly toward the plate 3 forming the horizontal side channels 13, 13.

There is a plate like head 14 in the housing located between the plates 10, 10 and this head has the lateral pintles 15, 15 whose outer ends are formed with the enlarged bearing members which work in the vertical grooves 12, 12. The head 14 has a central opening 17 through which the drill pipe, or other inner pipe 18 may work. The head has the opposing pairs of slots 19, 19, the slots of one pair being aligned with the corresponding slots of the other pair and depending from the said head 14 are the slip segments 20, 20. These segments are arranged in confronting relation and each segment is substantially arcuate in cross sectional contour, the outer sides of the segments tapering downwardly to conform to and fit snugly within the seat 5, the inner sides being vertically grooved and thus formed to closely fit around the pipe 18 when in active position. Suitable bolts 21 are fitted through the slots 19 and are screwed into the corresponding segments be- 100

neath and the upper ends of these bolts are enlarged and formed into conical shaped heads which serve to provide a sliding connection between said respective segments 5 and head 14.

Depending from the top of the housing are the pairs of guides 22 having the upwardly and outwardly inclined bearing faces 23 aligned above the corresponding heads of 10 the bolts 21.

The respective end plates 10 have the transversely aligned bearing slots 24 which receive the corresponding pintles 15. These slots are diagonally disposed and their inner 15 ends have a less pitch, relative to the vertical, than their outer ends thus providing the upper and lower bearing faces 25, 26 to work against the respective pintles 15 for a purpose to be hereinafter stated.

20 In carrying on drilling operations the slip segments are actuated into inactive position, as shown in Figures 1, 2 and 3. This is accompanied by turning the shaft 7 in an appropriate direction to move the yoke 9 out-

25 wardly and the bearing slots are so disposed that as the plates 10 move outwardly the pintles 15 and head 14 will be forced to move upwardly thus carrying the slip segments 20 upwardly and as they move upwardly the heads of the bolts 21 will strike against the bearing faces 23 and be moved outwardly carrying said segments outwardly with them clear of the opening 17. Drilling operation may now be carried on 30 through the apparatus. In case gas is encountered and a blowout is threatened the shaft 7 may be rotated in the opposite direction forcing the yoke 9 and plates 10 inwardly thus permitting the segments 20 to

35 move downwardly, and their lower ends, which are beveled inwardly as at 27, will strike the downwardly converging guide face 6 and said segments will move downwardly and inwardly into the seat 5 about 40 the inner pipe 18. When the slip is seated in said seat 5 the bearing faces 25 will be in contact with the pintles 15 and a further rotation of the shaft 7 will have the effect of wedging said faces 25 against the upper 45 sides of said pintles thus forcing the slip segments 20 downwardly and seating them securely in said seat and about said inner pipe so that there can be no leakage past them.

50 55 The lower ends of each segment 20 is equipped with suitable packing rings as 28 which extend entirely around each segment and form a seal not only between the segments and the seat 5 but between the segments and the inner pipe 18 as well as between the segments themselves.

The escape of fluid between casing and inner pipe will thus be entirely prevented.

60 65 When it is desired to move the slip segments again into inactive position the rota-

tion of the shaft 7 may be again reversed and the bearing faces 26 will now operate against the lower sides of the pintles 15 with wedge-like effect thus easily unseating said segments to permit them to be elevated and moved apart into inactive position as shown in the figures.

70 The side channels 13 are provided for convenience in assembling or dismanteling the apparatus so that the bearing members 16 may be moved into position in alignment 75 with the side grooves 12 or may be moved out of the casing when it is desired to remove the head 14 from the casing.

75 The segments 20 may be readily removed, 80 by removing the end plate 3 and unscrewing the bolts 21, and others substituted therefor so that slip segments may be provided to fit any size of inner pipe being used.

85 The well casing 2 has opposing internally threaded nipples 29 for the reception of the usual valve controlled flow lines so that the fluid in the well may be relieved therefrom.

90 The drawings and descriptions disclose what is now considered to be a preferred form of the invention by way of illustration only while the broad principle of the invention will be defined by the appended claims.

95 What I claim is:

1. Apparatus for forming a seal between an outer pipe and an inner pipe in a well bore comprising a housing on the outer pipe, vertical tracks in said housing, a vertically movable head having side pintles whose outer ends move along said tracks, a seat in the bottom of the housing around the inner pipe therein, slip segments depending from and laterally movable relative to said head, a yoke movable in the housing and having side plates provided with bearing slots in which said pintles move, an actuating shaft having a swiveling connection with the housing and a threaded connection with said yoke and by which said yoke and plates may be actuated, said bearing slots being shaped to effect the elevation of said slip segments when said yoke is moved in one direction and to permit the descent thereof into said seat, when the yoke is moved in another direction.

9885 9890 9895 9900 9905 9910 9915 9920 9925 9930 9935 9940 9945 9950 9955 9960 9965 9970 9975 9980 9985 9990 9995 10000 10005 10010 10015 10020 10025 10030 10035

with said yoke and by which said yoke and plates may be actuated, said bearing slots being shaped to effect the elevation of said slip segments when said yoke is moved in one direction and to permit the descent thereof into said seat, when the yoke is moved in another direction, guides in said housing and means carried by said segments shaped to contact with said guides and move said segments apart upon the elevation of the head.

3. Apparatus for forming a seal between an outer pipe and an inner pipe in a well bore comprising a housing on the outer pipe having a seat around the inner pipe, a vertically movable head in the housing, slip segments depending from and laterally movable relative to said head, a yoke movable in the housing, means operatively connecting the yoke with said head, an actuating shaft having a swiveling connection with the housing and a threaded connection with the yoke and by which the yoke may be actuated, said connections between the yoke and head being effective to elevate the head when the yoke is moved in one direction and to permit the head to descend when the yoke is moved in the other direction.

4. Apparatus for forming a seal between an outer pipe and an inner pipe in a well bore comprising a housing on the outer pipe, a seat in the housing around the inner pipe, a vertically movable head in the housing, slip segments depending from and laterally movable relative to said head, a yoke movable in the housing, means operatively connecting the yoke with said head, an actuating shaft having a swiveling connection with the housing and a threaded connection with the yoke and by which the yoke may be actuated, said connections between the yoke and head being effective to elevate the head when the yoke is moved in one direction and to permit the head to descend when the yoke is moved in the other direction, guides in said housing and means carried by said segments, shaped to contact with said guides and move the segments apart upon the elevation of the head.

5. Apparatus for forming a seal between an outer pipe and an inner pipe in a well bore comprising a housing on the outer pipe having a seat around the inner pipe, a vertically movable head in the housing, slip segments depending from and laterally movable relative to said head, a yoke movable in the housing, means operatively connecting the yoke with said head, an actuating shaft having a swiveling connection with the housing and a threaded connection with the yoke and by which the yoke is moved in one direction and to permit the head to descend when the yoke is moved in the other direction, a guide in said housing to direct

said segments into said seat on the downward movement of the segments.

6. Apparatus for forming a seal between an outer pipe and an inner pipe in a well bore, comprising a housing on the outer pipe having a downwardly tapering seat at the bottom thereof, an upwardly and outwardly inclined guide in said housing above said seat, a vertically movable head in said housing, a slip shaped to fit into said seat and formed of separate segments which depend from and which are movable laterally relative to said head, means operatively connected with the head and movable in one direction to effect the elevation of said head and segments and in another direction to permit said head and segments to move downwardly to seat said segments in said seat, said guide being effective to direct the segments into the seat upon the downward movement of the segments.

7. Apparatus for forming a seal between an outer pipe and an inner pipe in a well bore, said apparatus comprising a housing on the outer pipe, a vertically movable head in the housing, means confining the head to a substantially vertical movement in the housing, a seat beneath said head in the housing adapted to surround the inner pipe therein, segments depending from and laterally movable relative to said head, shaped, when assembled, to surround said inner pipe, a member in the housing operatively connected with the head and effective when moved into one position to elevate said head and segments and when moved into another position to cause said head and segments to descend and the segments to seat in said seat in assembled relation about the inner pipe, and means for actuating said member into either of said positions.

8. Apparatus for forming a seal between an outer pipe and an inner pipe in a well bore, said apparatus comprising a housing on the outer pipe, a vertically movable head in the housing, means confining the head to a substantially vertical movement in the housing, a seat beneath said head, in the housing, adapted to surround the inner pipe therein, segments depending from and laterally movable relative to said head, shaped when assembled, to surround said inner pipe, a member in the housing operatively connected with the head and effective when moved into one position to elevate said head and segments and when moved into another position to cause said head and segments to descend and the segments to seat in said seat in assembled relation about the inner pipe, means for actuating said member into either of said positions, said actuating means including a shaft having a swiveling connection with the housing and a threaded connection with said member.

9. A blowout preventer including a hous-

ing, a movable carrier plate disposed therein, said housing and plate having central passages therethrough to receive a pipe, a pair of closure members carried by said plate and movable with respect thereto, means movable laterally to actuate said plate and said members to move said members to open or closed position about said pipe.

10. A blowout preventer including a housing, a movable carrier plate disposed therein, central passages through said housing and plate, a pair of closure members carried by said plate and movable with respect thereto, means movable laterally to actuate said plate and said members to move said members to open or closed position, said means including side plates.

11. A blowout preventer including a housing, a movable carrier plate disposed therein, central passages through said housing and plate, a pair of closure members carried by said plate and movable with respect thereto, means movable laterally to actuate said plate and said members to move said members to open or closed position, said means including side plates, and slots in said side plates to guide said members.

12. In a blowout preventer, a housing, said housing having a vertical passage therethrough; a packing seat in said vertical passage, a trunnion plate within said housing, said trunnion plate being vertically movable therein; segmental packing elements, said packing elements being suspended from said trunnion plate and adapted for lateral movement with relation thereto, said packing elements also being adapted to form a seal within said packing seat; means to vertically actuate said trunnion plate, and means to move said packing elements cooperatively therewith.

In testimony whereof I have signed my name to this specification.

REUBEN L. WAXLER.
